UNITED STATES PATENT OFFICE.

ALFRED F. REILLY, OF ATTLEBORO, MASSACHUSETTS, ASSIGNOR TO EVANS CASE COMPANY, OF NORTH ATTLEBORO, MASSACHUSETTS, A CORPORATION OF MASSACHUSETTS.

DESIGN FOR A CASING FOR POCKET LIGHTERS.

Application filed December 2, 1927. Serial No. 24,368. Term of patent 14 years.

To all whom it may concern:

Be it known that I, ALFRED F. REILLY, a citizen of the United States, residing at Attleboro, in the county of Bristol, State of Massachusetts, have invented a new, original, and ornamental Design for a Casing for Pocket Lighters, of which the following is a specification, reference being had to the accompanying drawing, forming part thereof.

In the drawing, showing a casing for pocket lighters embodying my design, Figure 1 is a top view, Fig. 2 is a side elevation,

Fig. 3 is an edge view and Fig. 4 is a section taken as indicated by the line 4—4 in Fig. 2. The dominant features of my design reside in the fuel holder or casing portion of the lighter. The outer surfaces of the two side edges of the casing are concave, which gives the casing a distinctive and attractive appearance of extreme thinness when viewed from the edge.

I claim:

The ornamental design for a casing for pocket lighters as shown and described.

ALFRED F. REILLY.
